UNITED STATES PATENT OFFICE.

JOSEPH YATES, OF MOTT HAVEN, NEW YORK.

IMPROVEMENT IN THE MANUFACTURE OF IRON.

Specification forming part of Letters Patent No. 41,805, dated March 1, 1864.

To all whom it may concern:

Be it known that I, JOSEPH YATES, of Mott Haven, in the county of Westchester and State of New York, have invented certain new and useful Improvements in the Manufacture of Malleable or Wrought Iron; and I hereby declare that the following, taken in connection with the accompanying drawings, is such a full, clear, and exact description of the same, as will enable others skilled in the art to make and use the same.

My invention relates to the manufacture of iron by a direct process—that is to say, to the production of malleable or wrought iron directly from the ore. Furnaces or apparatuses for this purpose constructed or devised prior to this my invention were seriously defective, from the fact that the parts constituting such furnaces or apparatuses did not bear that relation to each other without which continuity and regularity of operation—the elements so essential to successful manufacture—could not be attained.

The present improvements have for their object the combination and arrangement of those parts of an apparatus or furnace for making malleable iron direct from the ore in which the ore is reduced, so that the operation therein effected may be carried on uninterruptedly in regular succession with greater uniformity throughout the whole apparatus at a greater saving of fuel, and with increased yield of metal, than this could ever be attained heretofore.

To this effect my invention consists, first, in the method, hereinafter described, of equalizing the temperature throughout all the chambers of the reducing-oven by increasing the capacity of said chambers in proportion to the intensity of the heat of the flame passing through them; secondly, in the method, hereinafter described, of equalizing the temperature throughout all the chambers of the reducing-oven by proportioning the area of the flues leading to and from the chambers in accordance with the intensity of the heat of the flame passing through said flue and chamber; thirdly, in the method, hereinafter described, of equalizing the temperature throughout all the chambers of the reducing-oven by so combining said chambers with flues that the capacity of the former and the area of the latter

are proportionate to the intensity of the heat of the flame.

In order to elucidate the principles of my invention, I shall briefly refer to the general construction, arrangement, and operation of the apparatus to which my improvement is applied.

The apparatus embodying my invention represented in sectional elevations according to the lines A B and C D in Figures 1 and 2, respectively, is composed of a reducing-oven, O, to which my present invention is particularly applied, of a chimney or stack, S, and of a welding-furnace, W. The reducing-oven O is a quadrangular structure erected on cast-iron columns at such height from the ground or base of the welding-furnace so that the latter, with the exception of the flues connecting it with the reducing-oven, shall be completely isolated, and also so that free access may be had thereto from all sides. Four columns, E, having girders F and arches G thrown from one to another, support the outer shell or structure of the oven, which is built of fire-brick, and strongly bound in by a net of cast-iron ribs or braces and wrought-iron tie-rods I. The top K and bottom L in the structure are formed of brick arches springing from one vertical wall to the other opposite. In this oven there is a vertical middle partition, M, running from top to bottom, dividing the oven into two equal main divisions, each of which is subdivided by transverse arched walls into chambers, called "reducing-chambers." The chambers of the reducing-oven intercommunicate by means of flues or passages, so that the flame or heated gases from the furnace pass first under the table or sole of the lower chamber, then over the said table, but under that of the upper chamber, and finally over the upper table and out of the upper chamber. The welding-furnace is combined with the reducing-oven by means of flues N for the passage of the flame or gases, and by means of receiving hoppers or channels P, through which the reduced ore is discharged from the reducing-chambers into the welding-furnace. The latter is constructed in the form of a puddling-furnace with a reverberatory roof depressed about midway to deflect the flame and concentrate the heat upon that portion of the hearth where the bloom is finally formed

previous to its being taken out from the furnace and carried to the hammer or squeezer. It is heated by a fire at Q, from which it is separated by a bridge, preferably hollow and open at the sides, to allow fresh air to circulate through it. The chimney or stack S is divided from the top down to the upper table by means of an angular partition-wall, T, whereby the flame or gases issuing from under the lower table are directed into the chamber above—*i. e.*, under the upper table and over the under table—and are then conveyed out of the upper chamber into the chimney, whence they are allowed to escape into the open air. The chimney is furnished at the top with dampers, which can be raised and lowered by means of a chain and lever, R, but which, during the working of the furnace are kept more or less closed, as the operations in the apparatus throughout all its parts are generally effected under pressure greater than that of the atmosphere.

Having thus given the outlines of a furnace to which my improvements are applied, I shall now briefly refer to the manner of working the same.

Charges of from fourteen hundred to eighteen hundred pounds of powdered coal and ore in the proportion of from twenty-two to twenty-five pounds of the former to one hundred pounds of the latter, properly mixed and prepared, are thrown through hoppers upon the tables and evenly spread over them and allowed there to remain, undergoing occasional stirring through doors T', provided in the sides of the oven, until the oxide of iron, under the combined influence of great heat and the presence of carbonic-oxide gas, shall be freed of its oxygen, converting the oxygen of carbon into carbonic-acid gas, which together with other gaseous matter are forced by the blast through the chimney, leaving iron in its metallic state, but mixed with impurities or cinders. At this state of the operation the table or tables are discharged directly into the welding-furnace—that is, the mass of reduced ore is thrown through the hopper upon the hearth, and the hot air is allowed to circulate about it, while it is kept constantly stirred, so as to expose fresh surfaces to the action of the gases, direct action of the atmosphere being all the time carefully avoided by keeping the working-door closed, otherwise the metal would be oxidized. When the particles of iron, &c., are thus converted into a pasty mass of sufficient consistency, it is pushed forward on the hearth opposite the balling-door, where the heat is very intense, being reverberated by the depression in the roof. The particles of iron now agglutinate and become soon welded, when the ball is seized by means of tongs and conveyed to the hammer and squeezer, under the action of which the slag is pressed out and the metal consolidated.

From the above it will be seen that the temperature of the flame and gases is higher in the welding-furnace than in the reducing-oven,

and that in the reducing-oven it must necessarily and gradually decrease from the point of ingress at the flue connecting it with the furnace to the point of egress—*i. e.*, at the flue connecting the upper chamber with the chimney. This is a source of great inconvenience, for the reason that the ore on the several tables, not being exposed to the same degree of heat, is in some places too highly heated, which injuriously affects the iron when reduced from the ore, while in other places it is exposed to a degree of heat insufficient to effect the composition of the ore in the manner hereinbefore referred to. On the other hand, the temperature not being the same throughout all the chambers, it was found necessary to allow the mixture of coal and ore to remain on the table exposed to the action of the flame and gases for a greater length of time in those chambers in which the temperature is less than in those in which it is higher, and the consequence was that the tables are necessarily discharged at irregular intervals of time, which greatly interfered with the proper working of the welding-furnace, and was wasteful of fuel because of the furnace periodically receiving more charges than could be conveniently worked, and of its periodically receiving less than is necessary to make good use of the heat derived at great cost of fuel. Again, the iron derived from the different charges indicated a want of uniformity of quality and texture greatly detrimental to this sort of manufacture. Thus one ball would be composed of tough and fibrous iron, while the other would be made of iron, brittle, and have all the characteristics of burnt iron; and, lastly, while in a certain part of the oven the production of iron was constantly a maximum, it was invariably less in the other parts, too great heat or insufficient heat having a tendency to reduce the iron to cinder.

The importance of my present invention will now be readily understood, its object being to equalize the temperature throughout all the chambers of a reducing-oven, and I accomplish this in three different ways:

First, by increasing the capacity of the chambers in proportion to the intensity of the heat of the flame passing through them. This may be effected in various ways. I prefer to make the tables parallel to each other and to the top or roof of the whole oven, and to give greater height to the lower chamber than to the upper chamber—that is to say, I make the distance between the two tables greater than the distance of the sole of the upper chamber to the roof of the oven. In Fig. 3 of the accompanying drawings, which is a sectional view similar to that in Fig. 1, the chamber U (supposing it to be of the same width as the chamber U') is shown somewhat higher than the chamber U', so that the flame or gases shall expand therein, while in the latter they are condensed, and consequently throw out more caloric.

Second, by proportioning the area of the

flues leading to and from the chambers in accordance with the intensity of the heat of the flame passing through said flues. This is carried into effect by making the orifice of the exit-flue smaller, and the ingress-flue larger in that chamber in which it is proposed to increase for the purpose of equalizing the temperature throughout all the chambers. Thus by making in the lower chamber the ingress-flue X X' smaller than its egress-flue Y, and at the same time making the ingress-flue Y to the upper chamber larger than its egress-flue Z the desired result will be obtained—that is, the two chambers will be heated uniformly—for the reason that while the flame is somewhat restrained from entering the lower chamber, yet free to issue from it, it is free to enter, but slow to issue from, the upper chamber, the effect of which under the influence of the pressure of the blast will be that the gases will emit more heat in proportion to their loss of temperature in passing from one chamber to the other.

Third, by so combining chambers with flues that the capacity of the former and the area of the latter shall be proportioned to the intensity of the heat of the flame. This is the mode which I employ in preference to others to carry into effect my said invention. By it a proper harmony of structure may be attained which produces the most beneficial results. Thus without effecting the object by only increasing or decreasing the capacity of the chambers, or by only increasing or decreasing the area of the flues to and from the chambers, both means may be combined, as

shown in the accompanying drawings, so that the disturbing effects of too great a contraction in any part of the oven may be avoided, and a free and easy passage of the flame and gases secured.

Having now fully described my improvements and the manner in which the same are or may be carried into effect, I shall state my claims as follows:

1. The method hereinbefore described of equalizing the temperature throughout all the chambers of the reducing-oven by increasing the capacity of said chambers in proportion to the intensity of the heat of the flame passing through them, substantially as set forth.

2. The method hereinbefore described of equalizing the temperature throughout all the chambers of the reducing-oven by proportioning the area of the flues leading to and from the chambers in accordance with the intensity of the heat of the flame passing through said flue and chamber, substantially as set forth.

3. The method hereinbefore described of equalizing the temperature throughout all the chambers of the reducing-oven by so combining said chambers with flues that the capacity of the former and the area of the latter are proportionate to the intensity of heat of the flame, substantially as set forth.

In testimony whereof I have signed my name to this specification before two subscribing witnesses.

JOSEPH YATES.
